UNITED STATES PATENT OFFICE.

JULIUS JAEGER, OF RUTHERFORD, NEW JERSEY.

SHEET-METAL CASING FOR BOTTLES.

SPECIFICATION forming part of Letters Patent No. 364,417, dated June 7, 1887.

Application filed September 17, 1886. Serial No. 213,783. (Model.)

To all whom it may concern:

Be it known that I, JULIUS JAEGER, of Rutherford, Bergen county, New Jersey, have invented certain new and useful Improvements in Sheet-Metal Casings for Bottles, &c., of which the following is a specification.

The object of my invention is to provide a new and improved sheet-metal casing for packing bottles or like fragile articles for transportation, and for containing and holding liquids, or finely-powdered or viscous substances, which casing is strong, can resist very powerful compression strains, can be closed hermetically, and opened and closed easily and rapidly.

The invention consists in a sheet-metal casing having circumferential corrugations closed by a screw-cap, and that part of the casing adjacent to the opening provided with external beads, all as will be fully set forth hereinafter, and finally pointed out in the claim.

In the accompanying drawings, Figure 1 is a longitudinal sectional view of my improved sheet-metal casing for bottles, &c., on the line xx , Fig. 2. Fig. 2 is a sectional plan view of the same on the line yy , Fig. 1. Fig. 3 is a cross-sectional view of the double-lock joint before it is compressed. Fig. 4 is a cross-sectional view of the same compressed.

Similar letters of reference indicate corresponding parts.

The sheet-metal case A is formed of two cylindrical or like sections, A' A'', drawn from sheet metal without seams and united by a double-lock joint, a, the several layers of which are pressed firmly together to form a solid exterior circumferential bead on the casing. The casing A is also provided with numerous hollow circumferential ribs, C, which are formed by means of a lathe, or in any other suitable manner. The bottom of the casing is made integral with the bottom section, A''. The section A' is provided at its upper end with a screw-thread, D, which is formed directly adjacent to the uppermost bead or rib, C, an inwardly-projecting flange, E, being formed on the upper end of the screw-thread D. A screw-cap, E, which can be screwed on the thread D, is provided along the edge of the closed end with a hollow bead, N, into

which a packing-ring, G, is placed, which, when the cap is screwed on the casing, is pressed upon the flange F and forms a hermetically-sealed joint. When the cap is screwed on the casing, the bead N and the uppermost bead, C, of the casing project laterally a short distance farther than the screw-thread, and thus form guards for the same, thereby protecting the screw-thread from injury while handling the casing, or when the casing is accidentally subjected to blows or heavy compression strains.

The article to be protected is placed in the casing, and sawdust or any other suitable packing or protecting material or substance is packed between said article and the sides of the casing. The cap is then screwed on. The circumferential ribs C strengthen and stiffen the casing, so that the same can resist a very great compression strain, either laterally or longitudinally. The solid rib a, at or near the center of the casing, strengthens or stiffens the casing at its weakest point, said solid rib having greater resisting power against compression strains than the hollow ribs C.

Smaller casings can be made of a single piece and the solid rib omitted. The casing might be provided with longitudinal ribs; but I prefer the circumferential ribs. The screw-cap and the closed end of the casing may be provided with circumferential ribs.

Having thus described my invention, I claim as new and desire to secure by Letters Patent—

The combination, with a sheet metal casing having a screw-thread at one end, and a hollow bead directly below said screw-thread, which bead projects farther than the threads, said casing also having circumferential corrugations on the space between the bead and the opposite closed end of the casing, of a screw-cap which can be screwed on the thread at the open end of the casing, which cap has a bead, M, substantially as shown and described.

In testimony that I claim the foregoing as my invention I have signed my name in presence of two subscribing witnesses.

JULIUS JAEGER.
